UNITED STATES PATENT OFFICE.

WALTER WRIGHT, OF KALGOORLIE, WESTERN AUSTRALIA, AUSTRALIA, ASSIGNOR
OF SIX-EIGHTHS TO BENJAMIN WEISS, OF PERTH, WESTERN AUSTRALIA, AUS-
TRALIA.

RAILWAY SIGNALING AND COLLISION-PREVENTION APPARATUS.

Application filed May 1, 1919. Serial No. 293,981.

To all whom it may concern:

Be it known that I, WALTER WRIGHT, a subject of the King of Great Britain and Ireland, residing at Forest Lodge, McDonald Street, Kalgoorlie, in the State of Western Australia, Commonwealth of Australia, have invented certain new and useful Improvements in Railway Signaling and Collision-Prevention Apparatus; and I do hereby declare the following to be a full, clear, and exact description of the invention, such as will enable others skilled in the art to which it appertains to make and use the same.

15 This invention relates to train control apparatus, and is directed more particularly to an apparatus of the type in which there is provided a train projection, rotatable from a clear to a danger position, with relation 20 to a valve seat, and which is in communication with the air under pressure of the air brakes.

In accordance with the invention, there is provided a train projection to be moved 25 from a clear position to a danger position by striking a train stop, which has been arranged in danger position. The apparatus is formed to provide a port which in the clear position of the projection connects air 30 under pressure through a valve seat with mechanism, connected to the engine motive power, and so arranged that when the projection is moved into its danger position, the air connection is cut off, the air allowed 35 to escape to the atmosphere, and the engine motive power cut off.

The invention is illustrated in the accompanying drawings, in which:

Fig. 1 is a view in elevation showing the 40 parts in normal positions.

Fig. 2 is a similar view with the parts in operative positions.

Fig. 3 is an elevation of the valve.

Fig. 4 is an elevation of the valve seat and 45 air conduits leading therefrom.

Fig. 5 is an elevation with the valve in normal position and the air brakes cut off.

Fig. 6 is an elevation with the valve in operative position.

50 To produce movement of parts of this train stop to the danger position, there is a connection from a motor to the train stop.

A projection 20 is mounted strongly to withstand shock, as by being in part enclosed

by a bracket 20^t movably mounted as on a 55 pivoted shaft 21 carried by the engine. This shaft may extend through a hole 21^a in arm 20 and its seat.

The engine cab X^c contains a lamp G to show a light (such as green) when required 60 to mean that the section ahead is clear, and contains a bell Z to ring when the light shows. Both lamp and bell are by means of wire 30^c (there being a frame return) in circuit with a switch button 20^a on the projection 65 20.

When a train (Fig. 1) reaches the ramp in raised or clear position, the projection 20 passes under that ramp, but an arm or cam which is provided projecting under that 70 ramp will be struck by the button 20^a, which will be depressed, so that the circuit aforesaid governed by this button becomes closed, causing lighting of lamp G and ringing of bell Z, and thus informing the driver he has 75 passed a clear signal. On being so depressed, the button 20^a becomes latched (by means that will be well understood and are not shown) and remains so, until the engine driver releases it by suitable means, as a 80 push button 30^b on a Bowden wire 30^b.

Each arm 20 is of suitable length, having anti-friction means, as roller 20^b, to strike parts of the train stop. Each train stop has a covering 27^k, as a protection 85 against, for example, the weather.

There is in the engine cab or the like a connection 31 from a valve arm 20, by which to open a shutter 31^a, causing exposure of a red light 31^b or a like signal. 90 When a signal is at danger and the arm 20 overruns its train stop, and is raised, it moves part 31 to show the red light and the arm is kept raised by for example, a notch 20^m in it becoming engaged by a latch 95 20^p on the engine frame.

Then the driver must before he can back the train, detach the latch, to do which he may be made to leave his cab. Valve arm 20 has a longitudinal breakage detecting 100 passage 20^j which extends to the outer end of the arm and has a port 20^k for connecting purposes stated below. If an arm 20 were to be broken, it would allow air from the train pipe 34 to escape freely, and would 105 cause the brakes to be applied.

The valve seat is mounted on the engine frame, and has a port 20^l and other ports

20^f, 20ⁱ, 20^e, and 20^g connected to tubes, one of which 38, is connected to the atmosphere; another 33, connects with air under pressure in the train pipe 34 of the air brake system, 5 and connects with a port 20ⁱ of the valve seat, which is always open to the valve passage 20ⁱ.

When arm 20 is raised, its port 20ⁱ is (see Fig. 6) through port 20ⁱ—connected to 10 port 20^f and by pipe 38 to the atmosphere, and the train brakes accordingly become automatically applied.

A power device, shown as a reservoir 36 of air under pressure, is provided on the engine 15 having a feed tube 37 to one end of a cylinder 20^e, and a feed tube 35 to the valve seat port 20^g. In the normal position of the arm 20, the latter port communicates as in Fig. 5 by means of the valve port 20^e 20 with the valve seat port 20^g which is open to a tube 20^d which leads into the other end of cylinder 20^e, so that the air pressure at each end of that cylinder is normally equal, and will sustain a piston 32 therein in a 25 central position, assisted by a spring 32^a, at each side of the piston.

The piston is mounted on a rod 32^b, which is connected to a control (not shown) of the engine motive power, so that in whichever 30 direction the piston and its rod 32^b are moved, that power will be cut off. Movement of the rod 32^b occurs when arm 20 is raised, because the port 20^g connects through port 20^k with the adjacent port 20ⁱ, letting 35 air from the cylinder escape by pipe 20^d and tubes 38.

This causes the air pressure through pipe 37 to be effective in moving the piston.

Duplicates as 20^D, 33^D, and 35^D of various 40 parts shown at the left in Figs. 1 and 2, are provided on the right and there are duplicates (not shown) of parts 31 and 30^a and 30^b. The parts G, Z, 31^a, 20^e, 36, will be operated from one side or the other of the 45 engine according to the ramps of train stops, which projections 20 pass so that references herein to part 20 mean to that part on the side where such part coats with a train stop, while the part 20 on the other side 50 remains unaffected.

When a train overruns a danger signal and its lowered front ramp, this ramp raises arm 20, which becomes latched, the brakes become applied, the engine power becomes 55 cut off and the red light is shown in the cab.

Having now particularly described and ascertained the nature of my said invention and in what manner the same is to be performed, I declare that what I claim is:

60 1. The combination with an engine cab, of an arm pivotally carried thereby and adapted to be tilted, said arm having a lon-

gitudinal passage 20^j extending to the outer end thereof and also having a port 20^k, a compressed air reservoir, a valve seat having ports 20ⁱ, 20^f, 20^e, 20^g and 20^k, a tube 33 in communication with the port 20ⁱ and adapted to receive air under pressure, a tube 35 in communication with port 20^g and with the compressed air reservoir, a tube 20^d in communication at one end with port 20^e, a tube 38 in communication with the atmosphere and also with ports 20^f and 20ⁱ, the said port 20ⁱ being always in communication with the passage 20^j, a cylinder with which the tube 20^d communicates, a tube 37 leading from the compressed air reservoir into said cylinder to feed compressed air into the latter, a spring-pressed piston arranged within the cylinder, a rod upon which the piston is mounted and adapted to be connected with a motive power control on the engine 80 so as to operate said control when said rod is moved in either direction, the various tubes and ports being relatively so arranged that when the pivoted arm is raised, port 20ⁱ will, through port 20^k, be connected to port 20^f 85 and by tube 38 to the atmosphere to cause the train brakes to be applied, and the port 20^e will connect through port 20^k with port 20ⁱ to permit air to escape by pipe 20^d and tube 38 to cause the air pressure in tube 37 90 to move the piston and its rod to cut off the motive power.

2. The combination with an engine cab, of an arm pivotally carried thereby and adapted to be tilted, said arm having a longitudinal passage extending therethrough and also having a port 20^k, a compressed air reservoir, a valve seat having ports 20ⁱ, 20^f, and 20^g, a tube 35 in communication with port 20^g and with the compressed air reservoir, 95 a tube 20^d in communication with port 20^e, a tube 38 in communication with the atmosphere and also with port 20ⁱ, a cylinder with which tube 20^d communicates, a tube 37 leading from the compressed air reservoir 100 into said cylinder to feed compressed air into the latter, a spring-pressed piston arranged within the cylinder, a rod upon which the piston is mounted and adapted to be connected with a motive power control on the engine 105 so as to operate said control when said rod is moved in either direction, the various tubes and ports being relatively so arranged that when the pivoted arm is raised the port 20^e will connect through port 20^k with port 110 20ⁱ to permit air to escape by tube 20^d and tube 38 to cause the air pressure in tube 37 to move the piston and its rod to cut off the motive power.

In witness whereof I have hereunto set 115 my hand.

WALTER WRIGHT
